BARRICADE

Robert H. Nygaard, 4701 Libra Place,
Yorba Linda, Calif. 92686

Filed Jan. 19, 1970, Ser. No. 20,987

Term of patent 3½ years

Int. Cl. D29—99

U.S. Cl. D72—1

FIG. 1 is a perspective view of a barricade showing my new design;

FIG. 2 is a top plan view of the barricade on an enlarged scale;

FIG. 3 is a front elevational view thereof;

FIG. 4 is a side elevational view thereof.

I claim:

The ornamental design for a barricade, substantially as shown.
